UNITED STATES PATENT OFFICE.

JAMES C. COVERT, OF WEST TROY, NEW YORK.

DESIGN FOR A BREAST-STRAP PROTECTOR.

SPECIFICATION forming part of Design No. 25,416, dated April 21, 1896.

Application filed February 14, 1896. Serial No. 579,319. Term of patent 14 years.

To all whom it may concern:

Be it known that I, JAMES C. COVERT, a citizen of the United States, residing at West Troy, in the county of Albany and State of New York, have invented and produced a new and original Design for a Breast-Strap Protector; and I do hereby declare the following to be a full, clear, and exact description of the same, reference being had to the accompanying drawings, forming a part thereof.

This invention relates to a new and original design for a harness breast-strap protector; and it consists in the peculiar shape and arrangement of parts hereinafter referred to and shown.

In the accompanying drawings, wherein the design is illustrated, Figure 1 is a perspective view of a protector embodying the invention. Fig. 2 is a longitudinal central section of the same.

The design consists of a peculiarly-fashioned frame, as shown, wherein A and A' designate two side bars, having their end portions diverging from a curved central portion and connected at their outer ends by the un-

derlying cross-bars B B'. The central curved portion of the side bars are connected by a loop or arched bar C, which projects below the plane of the side bars. The bars A and A' are connected along their upper edges for a short distance, and at points between the ends and the curved centers by the flat webs or plates D and D'. The exact position of these plates is immaterial, so long as the general appearance of the frame is maintained. 35

The essential feature of the design is the curved side bars having their ends connected by the cross-bars, the plates, and the lower arched connecting-loop C.

Having thus described the invention, what 40 is claimed as new, and desired to be secured by Letters Patent, is—

The design for a breast-strap protector, substantially as shown and described.

In testimony whereof I affix my signature 45 in presence of two witnesses.

JAMES C. COVERT.
